UNITED STATES PATENT OFFICE.

ALEXANDER RODGERS, OF MUSKEGON, MICHIGAN.

EDGING-CUTTER.

SPECIFICATION forming part of Letters Patent No. 310,321, dated January 6, 1885.

Application filed July 28, 1884. (No model.)

To all whom it may concern:

Be it known that I, ALEXANDER RODGERS, a citizen of the United States, residing at Muskegon, in the county of Muskegon and State of Michigan, have invented certain new and useful Improvements in Edging-Cutters, of which the following is a specification, reference being had therein to the accompanying drawings.

10 Figure 1 is a plan of the machine with the saw-cover removed. Fig. 2 is a transverse vertical section of the machine, showing the arrangement of the saws with relation to the stationary and swinging tables. Fig. 3 is a 15 side elevation of the same. Fig. 4 shows an adaptation of the machine operating with a single table, and Fig. 5 represents a modification in which the wipers or devices which carry the edgings from the tables to the saws have 20 a different form.

The object of this machine is to produce an apparatus that, with the least expenditure of floor-space, shall be capable of cutting up and disposing of the refuse from the largest mills 25 in an efficient and economical manner; and the invention consists in the arrangement, preferably beneath the floor of the mill upon which the lumber-cutting saws are located, of an arbor carrying a series of circular saws, in 30 connection with a stationary table upon which the refuse is received, and suitable devices for carrying said refuse from the tables to the saws, as will be hereinafter fully described.

In the several figures of the drawings, A 35 may represent the working floor of a saw-mill upon which the lumber-cutting saws are situated. Beneath this floor, and supported by posts B B, are placed the operative parts of the machine. The saw-arbor C, provided with the 40 series of circular saws *a a*, is carried in journal-boxes *b*, secured to the girts B'; or, if desired, other suitable supports for these journal-boxes may be provided. A cover, D, having oppositely-inclined sides, is placed over the saws, 45 the top of said cover being preferably on a level with the mill-floor, so that an opening, A', is left upon each side of said cover through the floor for the passage of the edgings or other refuse to the stationary tables E, which 50 are placed upon opposite sides of the saws, at a point a little below the horizontal line of the saw-arbor, and extend inward from each

side toward a vertical line drawn through its center far enough to give a firm support to the edgings while the saws are cutting through them, slots *c c* being formed in the edges of the tables, as shown in Fig. 1, for the reception of the saws.

Hinged to the posts B are the swinging tables F F, which, when hanging in a vertical position, just clear the top of the stationary tables, as at the right in Fig. 2; but when raised, as shown at the left of the same figure, extend across the opening and form, in connection with the inclined sides of the cover D, a hopper that receives and holds the edgings while the saws are cutting those which have already passed through to the stationary tables.

In order to give a proper movement and support to the swinging tables and at the same time carry the edgings upon the stationary tables forward to the saws, the shafts G G, carried in journal-boxes *d d* upon the girts B", and rotated in the manner hereinafter described, are provided with a series of arms or wipers, H H, which pass through the slots or openings *c' c'* in the stationary tables. Their outer ends coming in contact with the cleats *e e*, secured to the outside of the swinging tables, cause the latter, as the shafts rotate, to be raised up, so as to form, in conjunction with the inclined sides of the cover, a hopper, which, as heretofore described, holds the edgings which may accumulate during the passage of those which may already be upon the stationary tables through the saws, the time during which the edgings are held up by the swinging table depending upon the form given to the ends of the wipers, as these ends form a greater or less portion of the arc of a circle, and are consequently a longer or shorter time in passing a given point. As the rotation of the wiper-shafts continues the edges of the wipers are brought in contact with the slabs or edgings upon the stationary tables, which are then carried forward to the saws, and being cut by the same drop from the inner ends of said tables into a receiver, or upon a suitable conveyer, by which they are carried to a place of deposit.

The method of imparting motion to the several parts of the machine which I prefer is by a belt from any suitable pulley upon the mill-

shafting to the pulley I upon the saw-arbor, a smaller pulley, J, upon the same arbor, conveying motion through a belt to the pulley K upon the shaft L, which carries the pinion N, gearing into the large spur-gear P upon one of the wiper-shafts G. A similar spur-gear, P', is placed upon the opposite wiper-shaft, and so arranged that the action of the wipers upon opposite sides of the machine shall 5 be alternate, thus causing the edgings upon the stationary tables upon opposite sides of the saws to be moved forward in the same manner alternately, thus equalizing the labor upon the saws, as well as other parts of the machine.

15 In Fig. 4 is shown an adaptation of the machine to operate only upon one side of the saws, and with a single stationary table. Although containing substantially the same mechanical elements as that heretofore described, it evidently would have but half the capacity of the double machine, yet still this would be sufficient to do the work of many mills and would lessen the cost of construction.

20 25 In the modification shown in Fig. 5 a different form of the wipers is shown, the arms being three in number, the spaces between them forming arcs of circles which may be provided with teeth.

30 35 In this form of the machine the edgings are picked up from the stationary tables by the arms or wipers and carried forward to the saws resting upon said arms.

I am aware that it is not new to use a series 40 45 of circular saws mounted upon an arbor to cut edgings. Neither is it new to employ rotating carriers to convey the edgings from a slotted table to the saws; but the arrangement with these devices of a swinging table operated by the rotating carriers, causing an intermittent supply of edgings to the saws, and the combination therewith of the cover which protects them from injury by slabs or edgings falling from the floor, I believe to be new.

45 I claim as new and desire to secure by Letters Patent the following:

1. In a sawing-machine for cutting edgings and like refuse, the combination, with the saws *a a* and a hopper having a swinging table, F, adapted to form the bottom of said hopper when swung upward, and thereby give an intermittent supply of edgings to the saws, of a cover, D, arranged above the saws, and provided with an inclined side, substantially as described. 50

2. In a machine for cutting edgings, the combination, with the saws *a a*, the cover D, and a hopper having swinging tables F, of a rotary shaft, G, provided with arms or wipers H H, adapted to alternately raise and lower 60 said tables, whereby the edgings are supplied to the saws intermittently, substantially as described.

3. In a machine for cutting edgings, the combination, with the saws *a a* and swinging tables F F, having cleats *e e* on their under sides, of the rotary wiper-shafts G G and the arms or wipers H H, mounted thereon, substantially as described. 65

4. In a machine for cutting edgings, the combination, with the saws *a a*, of a hopper having stationary tables E E on each side, swinging tables F F, pivoted above the stationary tables, mechanism for raising the swinging tables alternately, and a cover, D, arranged above the saws and provided with oppositely-inclined sides, substantially as described. 70 75

5. In a machine for cutting edgings, the combination of a series of saws, *a a*, the rotary shafts G G, each having a series of arms or 80 wipers, H H, the cover D, arranged above the saws and provided with oppositely-inclined sides, and a hopper having stationary tables E E and swinging tables F F, substantially as described. 85

In testimony whereof I hereunto affix my signature in presence of two witnesses.

ALEXANDER RODGERS.
